UNITED STATES PATENT OFFICE.

WILLIAM O. FOWLER, OF WENATCHEE, WASHINGTON.

SWITCH-BOX.

1,069,777.

Specification of Letters Patent. Patented Aug. 12, 1913.

Application filed June 7, 1911. Serial No. 631,788.

To all whom it may concern:

Be it known that I, WILLIAM O. FOWLER, a citizen of the United States, residing at Wenatchee, in the county of Chelan and 5 State of Washington, have invented new and useful Improvements in Switch-Boxes, of which the following is a specification.

This invention relates to switch boxes and more particularly to that type which is 10 adapted for mounting flush wall switches. In mounting these switch boxes it is necessary that the switches therein be arranged flush with the plaster so as to properly receive the facing plate. Frequently, through 15 carelessness or the position of the supporting board or part, the box cannot be brought flush with the plaster and, in order to mount the switch plate, it is necessary to apply a number of washers and a long screw. This 20 was extremely inconvenient for if the correct number of washers were not placed upon the screw in the first instance the plate had to be removed and the operation tried over again.

25 It is the object of this invention to avoid these difficulties by providing means whereby the switch mounting arms may be adjusted upon the box so as to bring the switch flush with the plaster.

30 A further object of the invention is the provision of means for supporting the box upon a board or other support in such a manner that the square hole in the board, now necessary for the proper adjusting or 35 mounting of the box, may be dispensed with and a notch formed in the side of the board may be used. This lessens the labor of installation.

40 A still further object of the invention is the provision of a box having a removable side and spacing members adapted to coact with the box and with the removable side, so that additional switches may be mounted in the box when necessary.

45 Further objects of the invention will appear as the following specific description is read in connection with the accompanying drawings, which form a part of this application, and in which:—

50 Figure 1 is a vertical sectional view through a wall or partition showing the switch box mounted therein. Fig. 2 is a front elevation with the facing plate and a portion of the plaster removed. Fig. 3 is a 55 top plan view of the box. Fig. 4 is a section on the line 4—4 of Fig. 3. Fig. 5 is an inside

elevation of the adjusting mechanism removed from the box. Fig. 6 shows a top plan view of the box with the spacer applied. Fig. 7 is a detail section on the line 7—7 of 60 Fig. 3 on an enlarged scale. Fig. 8 is a perspective view of one of the spacers used.

In mounting these switch boxes and flush switches it has sometimes been the practice of electricians to connect them directly to the 65 laths. This, however, is not good practice and work of this character done by the best electricians includes a supporting board 1 which is mounted between a stud 2 and the partition 3. This makes a thoroughly reliable mounting and holds the switch steady.

70 The switch box comprises a substantially U-shaped frame 4 having the usual plugged passages for the conductor. Secured to this U-shaped frame is a side 5 which is made 75 permanent thereon in any suitable manner. The opposite side of the frame has mounted therein the screws 6 which are adapted to be engaged by the notches 7 formed in the lateral ears 8 of the removable side 9 and also 80 the notches in the lateral ears 10 of the U-shaped spacer, shown in Fig. 8. This spacer is also provided with screws 11 adapted to engage the lateral ears 8 of the side 9 when the spacer is applied to the frame 4. These 85 spacers may be applied in any number to the frame 4 or to each other so that a plurality of switches may be mounted in the box when necessary. Each side member has secured thereto, so as to be adjusted thereon, 90 the attaching brackets 12 provided with holes 13 to receive the attaching board 1, the supporting board being notched from one side, so as to receive the switch and permit the 95 brackets to lie upon opposite sides of the notch.

100 Each link of the U-shaped frame is provided, adjacent its free end, with a recess 14 formed by depressing the material of which the frame is formed in order that a socket may be formed to receive the switch mounting member or bracket 15. This member is 105 slidably mounted in the recess and is provided with a lateral finger 16 upon which the switch 17 is adapted to be attached by the screw 18. The opposite end of the bracket 15 is provided with an outward and laterally extending finger 19 in which is formed a screw threaded aperture 20 adapted 110 to receive the adjusting screw 21. This adjusting screw is journaled in the end 22

of a housing 23 which is secured over the socket 14 by means of screws 24, the screw being held against longitudinal movement in the end by means of a collar 25.

5 When the switch is secured to the bracket 15 within the box the screw 21 may be rotated in the housing and, as this screw has threaded connection with the lateral finger 19 of the bracket 15, the bracket 15 will be 10 adjusted inwardly or outwardly according to the direction of rotation of the screw and the switch thus positioned within the box, so that its outer surface will be flush with the plaster. The front plate 26 may then be 15 applied in the usual manner.

Having thus described the invention, what I claim as new is:—

1. In a device of the class described, the combination with a substantially U-shaped frame, of sides secured thereto, the ends of 20

said frame being recessed, brackets secured upon the sides for securing the box to a support, and means slidably mounted in the recesses for securing the switch in the box.

2. In a device of the class described, the combination with a substantially U-shaped frame having sides secured thereto, the ends of the box being recessed, brackets adjustably mounted upon the sides for securing the box upon a support, housings carried on the ends over the recesses, switch mounting members slidably mounted in the recesses, and means carried by the housings for adjusting said switch mounting members.

In testimony whereof I affix my signature in presence of two witnesses:

WILLIAM O. FOWLER.
